UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

CAR-WINDOW CONSTRUCTION.

1,097,677.

Specification of Letters Patent. Patented May 26, 1914.

Application filed March 12, 1913. Serial No. 753,762.

To all whom it may concern:

Be it known that I, HARRY H. SCHROYER, a citizen of the United States, and a resident of the city of Chicago, in the county of Cook and State of Illinois, have invented certain new and useful Improvements in Car-Window Constructions; and I do hereby declare that the following is a full, clear, and exact description of the same, reference being had to the accompanying drawings, and to the numbers of reference marked thereon, which form a part of this specification.

With the advent of the all-steel passenger coaches, the ordinary principles of construction of the window framing for the sliding sashes have proved inadequate, and it has become necessary to provide strong, and fireproof framing, preferably of metal. Hitherto, such metal construction has proved exceedingly heavy and complicated, and has not come into general use for such reason.

It is an object of this invention to construct a car window post of great strength and durability, and of extreme simplicity, composed of metal bars of standard section, together with stamped sheeting of relatively heavy gage, and also to be connected together.

It is also an object of this invention to provide a car window post having integrally connected and continuous walls shaped to afford the framing for the sliding window sashes.

It is finally an object of this invention to provide an exceedingly cheap, simple and durable construction consisting of few parts, and easy of assembly.

The invention (in a preferred form) is illustrated in the drawings, and hereinafter more fully described.

In the drawings: Figure 1 is a fragmentary exterior view in elevation of car windows equipped with a construction embodying the principles of my invention. Fig. 2 is a transverse horizontal section on line 2—2 of Fig. 1. Fig. 3 is an enlarged transverse horizontal section of a window post constructed on the principles of my invention.

As shown in the drawings: The window posts consists of a T bar 1, riveted to which, or otherwise secured on the flanges thereof, are channel members 2 and 3, of which the

member 3, is of slightly heavier construction and a trifle wider than the member 2, and is provided on its edges with the laterally extending flanges 4. Welded or otherwise secured between the flanges of said channel members 2 and 3, are the extremities of a jamb and cheek plate member 5, which extends inwardly in zigzag relation on each side to afford recesses 6 and 7, for inner and outer stops respectively. Relatively and detachably engaged in said recesses are the inner and outer stops 8 and 9, respectively, said stops being angled acutely at their extremities complementally with the walls of the recess. Riveted to the inwardly extending web of said T bar 1, are the Z bars 10, the outwardly extending flanges of which are secured by spot welding or other suitable means to the plate 5, at the bottom of the recesses 6. Thus it is seen that the continuous stamped jamb and cheek plate 5, affords the sides and end walls of the window post, while the inner channel 2, and the outer channel or cheek plate 3, riveted to the flanges of the T bar, form the end wall which is a part of the outer wall of the car.

Slidably mounted between the stops 8 and 9, are stiles 11, of the inner sliding sash, and slidable between the stops 9 and the flanges 4, are stiles 12, of the outer sliding sash. For the purpose of engaging the flange 4, the stile 12, is provided with a stepped recess, and fitted therein is a small T bar 13, with one flange thereof engaged in one of the stepped recesses and the other projecting outwardly to afford a groove for the reception of the flange 4. The flanges 4, of the cheek plate 3, thereby afford an outer stop for the outer sash, as well as weather proofing means, inasmuch as the pressure of the wind upon the outer sliding sash will force the same inwardly, thus causing the bar 13, to closely contact the flange 4, to afford a seal.

The operation is as follows: In the construction of the window post the Z bars 10 are first riveted to the web of the T bar and the channel members 2 and 3, likewise engaged upon the flanges of the T bar, and symmetrically spaced so as to receive the ends of the cheek plate 5, therebetween, which may be secured therein either by riveting or spot welding or any other suitable or convenient means, the post, of course,

being open at both ends for the purpose of performing such operation.

The jamb plate, which is shown as recessed, at 6 and 7, is also rigidly secured to the outwardly extending flanges of the Z bar's 10, preferably at the bottom of the recesses 6. As shown, said recesses have acutely angled or converging walls, and the removable stops adapted to be inserted there-in, are provided with resilient angled or divergent webs conforming to the configuration of the recess. Of course, when it is desired to remove or insert a sliding sash the stops are easily pulled out of the recesses, and may be easily sprung therein again when desired to replace the same. It will be noted that the only stress communicated to the stops by the sliding sashes is a transverse stress exerted normally on the contact walls of the stop, and this has no tendency to cause the stops to be forced from their recesses.

Of course, the details of construction em-

bodying the principles of my invention are open to wide variation, and I therefore do not purpose limiting the patent granted otherwise than necessitated by the prior art.

I claim as my invention:

In a window post construction a continuous jamb and cheek plate extending around one end and on both sides thereof and having correspondingly arranged recesses in the sides, a T bar inclosed thereby, Z bars secured to said plate and to said T bar, and an inner and an outer channel member secured on the flanges of said T bar and adapted to receive the extremities of said plate therebetween.

In witness whereof I have hereunto subscribed my name in the presence of two subscribing witnesses.

HARRY H. SCHROYER.
